2 Claims. (Cl. 117—37)

This invention relates to floor coverings, leathercloth, coated paper and the like with especial reference to so-called spread flooring, being sheet material having an upper or wearing surface in the form of an applied thermoplastic coating.

The base material may be any appropriate kind of fabric, felt, paper, metal foil or indeed any flexible sheet material which can be supplied in roll form.

The coating is applied in the form of a paste of thermoplastic material capable of being cured by heat and is suitably polyvinylchloride, P.V.C. cured by infra-red irradiation after being applied to the moving sheet under a doctor knife which defines the thickness of the applied coating.

The invention provides for the simultaneous application to the base material of coloured paste or coloured pastes of similar character via the doctor knife, prior to curing, so that a patterned upper or wearing surface is obtained.

The doctor knife through which the coloured paste is applied may be oscillatable and programme controlled to give variable patterns capable of repetition, and as will be appreciated there may be more than one different colour paste application, but all must be simultaneous with the application of the matrix of thermoplastic material forming the coating.

The cured coated sheet material may be given any desired surface finish, e.g. by passage of the coated sheet through suitably engraved rolls.

In the practice of the invention applied to the manufacture of sheet material coated with polyvinylchloride, paste for the matrix is advantageously supplied by gravity feed from a hopper or by hand to the surface of the base material as it approaches the doctor knife of the coating or spreading machine.

The additional pattern forming paste or pastes which may be transparent, white or coloured, may be applied through ducts in or associated with the doctor blade and may be fed by hydrostatic head from hoppers arranged above the doctor knife, preferably with valves in the connecting ducts.

The doctor knife is advantageously a composite structure with the ducts for the application of paste formed by co-operative grooves in mating components of the knife which can be dismantled and separated to facilitate cleaning.

The ducts are distributed at spaced intervals along the doctor knife, i.e. across the web of material passing through the coating or spreading machine, and where provision is made for transverse oscillation of the knife, it is preferred not to interrupt the supply of additional paste but to remove any surplus at each side of the web by scrapers or similar devices.

It has also been found advantageous to have the holes in the doctor knife of different sizes and this can be done most readily by having interchangeable jets fitting into the doctor knife. This further increases the patterns which can be produced and facilitates cleaning.

Programming of the doctor knife oscillation may be effected by a reversible electric motor, but the oscillation is preferably effected hydraulically suitably under the control of a programming device which may follow any

2

selected one of a plurality of patterns moving in synchronism with the passage of the web of base material through the spreading machine.

The programme may be in the form of a continuous or non-continuous band with perforations or serrated edge.

Alternatively, it may be a rotating disc with perforations, slots or serrations. The band or disc when fed through the sensing head of a hydraulic controller varies the pressure or vacuum set up in the system and thereby operates the hydraulic mechanism.

Alternatively, the band or disc may interrupt the beam of light in a photo-electric type of sensing head which in turn operates the hydraulic mechanism.

One embodiment of apparatus for carrying out the invention is shown in the accompanying drawings in which:

FIGURE 1 is a perspective view of the apparatus.

FIGURE 2 is a side view of a doctor knife taken on the lines II—II of FIGURE 3 while

FIGURE 3 is a front view of the doctor knife and

FIGURE 4 is a detail view taken in cross section on the lines IV—IV of FIGURE 3.

In the drawings 1 represents the continuous web of base material drawn from a supply roll 2 over a guide roller 3 and passing under a doctor knife generally designated 4.

The web then passes through an infrared oven 5 to pull-through rollers 6, the web being supported during its passage through the oven 5 on freely rotating rollers 7, 8 and 9.

Above the doctor knife 4 is a hopper divided into two separate containers 10a and 10b for polyvinyl pastes of the required colours for the pattern it is desired to form 11 and 12 are downcomer pipes leading from the containers 10a and 10b respectively to the doctor knife 4.

In this embodiment the main coating of polyvinylchloride paste for the web is applied to it by hand or from a third hopper by means of a duct or pipe, at a position ahead of the doctor knife where it passes over a table 14 between guards or vanes 20 and 21.

The doctor knife 4 is oscillatable laterally of the web 1 and its lateral position is determined by an hydraulic ram 22 controlled by a sensing head 23.

FIGURES 2, 3 and 4 show the doctor knife in greater detail. 24 and 25 are front and back plates which are clamped on opposite sides of the blade 38 of the knife by the bolts 37. 26 and 27 are ports through the plates 24 and 25 and provide communication between the down-comers 12 and 11 respectively, with galleries 28 formed in the blade 38. Leading downwardly from the galleries 28 are ducts 30 terminating in orifices 31.

From FIGURE 4 it will be seen that the orifices 31 are formed in steel sleeves 32 which are located in bores 34 formed for the purpose in the blade 38. Before the plates 24 and 25 are fixed to the blade 38 the sleeves 32 are passed from above into the bores 34 by way of the ducts 30 and are then rotated until shoulders 33 are engaged in recesses 35. If necessary the lower ends of the sleeves 32 are machined flush with the lower face of the blade 38. The sleeves 32 are removable for cleaning or replacement and sleeves with orifices of different sizes may be substituted so that the correct size may be employed for a particular pattern.

36 represents bolts which project into the ducts 30 and may be adjusted to control the flow of material through the ducts from galleries 28 to orifices 31.

The pull-through rollers 6 are driven by a belt or chain 29 from an electric-motor (not shown) it being understood that their speed of rotation regulates the rate at which the coated web 1 passes through the infra-red oven 5.

I claim:

1. A method of applying a coating of thermoplastic material capable of being cured by heat to a base material in sheet form, comprising applying a basic coating of thermoplastic material to a moving sheet of the base material, passing the moving coated sheet under a transversely oscillating doctor knife having an operative edge which defines the thickness of the applied coating, simultaneously, and while doctoring the base coating, applying through transversely spaced separate orifices in said operative edge, additional thermoplastic material of a character similar to the base coating but of a different color; and doctoring with said oscillating doctor knife said basic coating and said additional material while it is being applied to form a patterned coating on said sheet of base material, and subsequently curing said applied coating.

2. A method according to claim 1 wherein the additional thermoplastic material is applied through at least

two longitudinally spaced rows of transversely spaced separate orifices in the operative edge of said doctor knife.
